KARL F. NEILSEN, OF LONG BEACH, CALIFORNIA.

WELL HEATING AND PUMPING SYSTEM.

Application filed February 8, 1926. Serial No. 86,809.

As may be inferred from the above designation, this invention relates particularly to improved means for obtaining comparatively heavy hydrocarbon products from oil wells; and organizations of the type herein described may be used, with very notable advantage, in obtaining those mineral oils which run below about 13° Bé. in gravity,—many of these oils or oil mixtures as naturally occurring in California and elsewhere being, when cool, so stiff that one may actually walk upon them, although sufficiently fluid when heated, as by steam, to permit the pumping thereof by ordinary cyclically moving parts such as pumps comprising usual or special reciprocating plungers.

It is an object of this invention to provide a combination of the general character indicated, including a main pump, comprising moving parts, disposed above a heater to which a hot fluid such as steam is admitted, the movements of said main pump being incidentally effective to operate a subsidiary pump for the elevation of condensed water, or the like,—preferably through a pipe distinct from, but concentric with that through which oil, or the like, may be delivered by said main pump; and, in preferred embodiments of my invention the oil being delivered upward through a string such as a so-called "macaroni" string by which reciprocation of a main plunger is effected, and the water of condensation being by-passed, as pumped, to a level above the cylinder of the main pump, the pumped water may be elevated in a space surrounding the mentioned "macaroni" string serving as a pump rod, in such manner as to keep the delivered column of heavy oil comparatively hot, throughout the entire distance to the surface of the ground.

Other objects of my invention, including the provision of a heater of novel design, preferably provided with an air releasing valve and with means for confining air about a downwardly extending pipe through which condensed water is upwardly delivered past a foot valve, and comprising also means whereby the downward stroke of the plunger of a main pump is effective to force the con-

densing water upward through a valved by-pass or by-passes, and preferably comprising also an oil inlet fitting provided with a plurality of standing valves disposed eccentrically with reference to the moving parts of a main pump, may be best appreciated from the following descriptions of illustrative embodiments of my invention, taken in connection with the appended claims and the accompanying drawings, in which

Fig. 1^A is a substantially central vertical section through an organization illustrating my invention, as positioned in a well, Fig. 1^B being an upward continuation of Fig. 1^A.

Fig. 2 is a horizontal section, taken substantially as indicated by the line 2—2 of Fig. 1^A.

Fig. 3 is a view corresponding to Fig. 2, but illustrating a modification suitable for use in close quarters.

Referring to the details of that specific embodiment of my invention illustrated in Figs. 1^A, 1^B and 2,—11 being an outer casing such as is commonly provided in an oil well, or the like, 12 represents a comparatively small pipe, suitable for the delivery of a heating fluid, such as steam, past a control valve (not shown—being at the surface) to a heater or lower chamber 13, located at the level from which oil, or the like, is to be elevated; and this heater is shown as provided not only with an air release valve 14, adapted to permit replacement of air within the said heater by steam, but also with a substantially central pipe 15, comparable with the so-called gas anchor pipes commonly secured to the standing valves of reciprocating pumps,—this pipe 15 being carried to a level near the bottom of the heater 13, in order to permit a continuous or intermittent pumping of condensed water therefrom. The valve 14 is shown as retained by means of an interiorly threaded member 16 providing an additional seat 17 therefor; and the weight of the ball constituting valve 14 may be such as to cause the said valve, after opening, by a slight elevation of said ball, for a sufficient period to permit the escape of air, to close by further upward movement in response to an internal

steam pressure amounting to (say) five pounds,—the ball 14 then engaging the seat 17, and preventing further escape of steam into the surrounding oil or other liquid to be heated, an initial escape of steam, during a warming-up period, being sometimes useful for the purpose of rendering said liquid sufficiently fluent to be pumped.

Although most of the air originally contained within the heater 13 is permitted to escape in the described manner, in order to provide a thermal insulation about the pipe 15, through which water is to be elevated without revaporization, the pipe 15 is shown 10 as surrounded by a larger pipe 18, extending through the top 19 of the described heater and downwardly terminating at a level below the lower or inlet end 20 of the pipe 15,—the upper end of the outer pipe 18 being shown as threaded at 21 into a fitting 22 which provides a socket 23 for a standing valve organization comprising a valve cage element 24. This cage element, interfitting 15 within the socket 23, is shown as providing a seat for a ball valve 25 and as interiorly threaded, at 26, to receive the mentioned water pipe or leg 15; and condenser water may be "sucked" up past the valve 25, and delivered laterally into an exit or delivery pipe 27, shown as valved at 28, by any suitable 20 means, as by a plunger 29, shown as working in a barrel 30, shown as secured within the short section 31 of suitable pipe or tubing,—from which a lateral opening communicating, as by means of an elbow 32, with the water delivery pipe 27.

Above the described moving parts I show 25 a main pump 33 as comprising a plunger 34, within a liner 35 in a cylinder or shell 36, the plunger 34 being shown as reciprocable by a hollow rod 37 of the "marcaroni" type and as provided with a valve 28,—said rod having at 39 a threaded engagement with a cage fitting 40, by which the same is connected with the plunger 34. The connecting of the cage element 40 with the plunger 34, as by means of interior threads at 41 on the cage element 40, may be incidentally effective to retain a replaceable seat 42 in a known manner; and 35 between the threaded lower end 43 of the cylinder or shell 36 and the short pipe section 31 surrounding the replaceable cylinder 30 of the described subsidiary or water pump, I may interpose a valved oil inlet fitting 44 of any suitable design.

The oil inlet fitting 44, as shown in Figs. 1^A and 2, may comprise a cylindrical or upwardly diminishing body 45, interiorly threaded at its upper end for engagement 40 by corresponding threads upon the lower end 43 of the cylinder or outer shell of the described main pump; and the lower end of said inlet fitting, whether integral or provided in the form of a separate plate 46, having 45 threaded connection at 47 with said shell and

threaded connection at 48 with the pipe section 31 of the subsidiary pump, may be provided with any suitable number of oil inlet valves 49,—these valves being shown as secured by nipples 50 and as confined by cages 51.

Oil, rendered fluent by the described heater or by equivalent means, after its admission past the valves 49, upon an upward movement of the plunger 34 of the main pump 33 (the return of such oil being prevented by the closing of the valves 49) is compelled by the subsequent descent of the piston or plunger 34 to pass upwardly through a passage or passages 52, advancing past the valve or valves 38, in such manner as to be retained thereby and lifted, during a subsequent upward movement of the plunger 34; and, in order that each reciprocation of the plunger 34, or its equivalent, shall be effective correspondingly to reciprocate the plunger 39, of the described subsidiary pump, forcing water confined above the ball 25 into the by-pass pipe or pipes 27, I show the plunger 34 as connected with the plunger 39 by means comprising a rod 53, integral with the plunger 29, and a "spider" 54 threaded into both the plunger 34 and the rod 53, this "spider" being structurally similar to an ordinary valve cage of the type commonly used in standing valve organizations.

Although, when the particular construction above described is employed, the stroke of the plungers 29 and 34 is identical, it will be understood that the internal diameter of the subsidiary or water cylinder or liners 30 may ordinarily be very much less than that of the main or oil cylinders or liners 35, by as much as the condensed water is less in bulk than the heated oil pumped, but each upward movement of the main pump plunger 34, as produced by the reciprocation of the "marcaroni" pump rod 37 through which the pumped oil is delivered, is intended incidentally to remove such condensed water as may have collected upon the bottom 55 (preferably conical) of the heater 13; and each downward movement of the interconnected plungers must accordingly serve not only to force the heated oil or other fluid, handled by the main pump, relatively upward past the valve 28, or its equivalent, but to force the hot water or other heating fluid previously drawn into the space 56, above the valve 25, out past the valve or valves 28 and thence upward through the pipe or pipes 27. By returning said pipe or pipes 27 (as by means of an elbow or elbows 57) to a main string of tubing 58 surrounding the reciprocable "macaroni" string 37, I am able to utilize the residual heat of the condensed water in maintaining the temperature and consequent fluidity of the pumped oil during its delivery to the surface of the ground.

It will be obvious that the dimensions of

- the described parts are immaterial to the principles of my invention; but I may mention that, employing a heater about forty feet long within an eight inch hole, and employing 5 so-called four inch tubing in conjunction with two and one-half inch "macaroni", I have obtained eminently satisfactory results, elevating heavy oils, of the general character referred to, through vertical distances such as 10 1,000 feet more or less; but, in the case of very deep wells, the lowermost parts thereof being often of comparatively small diameter, I may commonly prefer to employ an oil inlet member 44^a of the alternative character illustrated 15 in Fig. 4. In this case, using a heater 13^a having but little clearance within the drilled hole or within a casing therein, and providing the oil inlet fitting 44^a (shown as having approximately the same diameter as the heater 13^a) with a flat side, as at 59^a, I may so dispose valves 49^a as to permit an ample inflow of heated oil, or the like, even though the mentioned flattening of the fitting 44^a results 20 in an unsymmetrical placing of said valves; and ample capacity is secured and space is provided for the pipes 12^a and 27^a (respectively corresponding to the mentioned pipes 12 and 27) substantially or entirely within a circle corresponding in diameter 25 to the heater 13^a and/or the oil inlet fitting 44^a.
- It will be obvious that steam, or the like, fed downward into pipe 12 (or 12^a) or its equivalent, may be given any desired superheat; and, although I have herein assumed 30 that condensed water is handled by the described subsidiary pump, it will be obvious that, in extreme cases, suction of the subsidiary pump 29 may be necessary only during an initial or warming up period,—steam being permitted during subsequent continuous 35 operation to advance upward past the valves 25 and 28 and to fill the space between the pipes 37 and 58 with uncondensed steam or other heating fluids. In any case, the lower 40 plunger 29 will be seen to be comprised in a means for conditioning the identical liquid which is to be elevated by the upper plunger 34.
- Although I have herein described a single 45 complete embodiment of my invention, suggesting one alternative construction of an oil inlet member, it should be understood not only that various features of my device are capable of independent use, but also that numerous modifications, additional to that suggested above, might easily be devised by those skilled in the art to which this case relates, without involving the slightest departure 50 from the spirit and scope of this invention, as the same is indicated above and in the following claims.
- I claim as my invention:
1. In a combined heating and pumping organization suitable for insertion in a well 55
- hole; a main pump comprising cyclically moving parts; means for conducting a heating fluid into proximity to said pump; and means whereby the cyclical movement of a part of said main pump is effective separately to 60 elevate any condensed portion of said heating fluid.
2. An organization of the general character defined in claim 1 in which said main pump is a reciprocating pump. 75
3. An organization of the general character defined in claim 1 in which said main pump is a reciprocating pump whose plunger is rigidly connected with the plunger of a pump constituting the mentioned means for the separate elevation of a condensed portion of said heating fluid. 80
4. In combination: means for elevating oil from a well; a steam heater in said well; and means facilitating a displacement of air from said heater, to permit the entrance of steam thereto. 85
5. In combination: means for elevating oil from a well; a steam heater in said well; and means facilitating a displacement of air from said heater, to permit the entrance of steam thereto, said last mentioned means comprising a valve which is closed, by a predetermined subsequent internal steam pressure. 90
6. A pumping organization which comprises an upper plunger; a lower plunger; separate cylinders surrounding each of said plungers; separately valved inlets to said cylinders; non-communicating delivery conduits respectively connected with outlets from said cylinders, the upper of said delivery conduits being central and centrally valved and the lower of said conduits being lateral and separately valved; and means, 95 between said plungers, rendering reciprocation of one of said plungers effective to produce reciprocation of the other of said plungers, and thereby to advance separate columns of liquid through the respective delivery conduits; and a conditioning organization including said lower plunger, said conditioning organization comprising a lower chamber adapted to receive a hot fluid for conditioning a liquid surrounding said chamber and which is to be elevated by said upper plunger. 100
7. A pumping organization which comprises an upper plunger; a lower plunger; separate cylinders surrounding each of said plungers; separately valved inlets to said cylinders; non-communicating delivery conduits respectively connected with outlets from said cylinders, the upper of said delivery conduits being central and centrally valved and the lower of said conduits being lateral and separately valved; and a connecting rod, between said plungers, rendering reciprocation of one of said plungers effective to produce reciprocation of the other of said plungers, and thereby to advance separate columns of liquid through the respective 105
- 110
- 115
- 120
- 125
- 130

delivery conduits and a conditioning organization including said lower plunger and a lower chamber adapted to receive a hot fluid for conditioning a liquid surrounding said chamber and which is to be elevated by said upper plunger,—said connecting rod being surrounded by an inlet fitting adapted to re-

ceive liquid to be elevated by said upper plunger.

In testimony whereof, I have hereunto set 10 my hand at Los Angeles, California, this 26th day of January, 1926.

KARL P. NEILSEN.
